UNITED STATES PATENT OFFICE.

THOMAS J. GORMAN, OF NEW YORK, N. Y.

CLOSURE FOR ENVELOPS AND THE LIKE.

No. 828,847.

Specification of Letters Patent.

Patented Aug. 14, 1906.

Application filed November 30, 1904. Serial No. 234,869.

To all whom it may concern:

Be it known that I, THOMAS J. GORMAN, a citizen of the United States of America, and a resident of the borough of Manhattan, New York city, in the State of New York, have invented a new and useful Improvement in Closures for Envelops and the Like, of which the following is a specification.

This invention relates to means for securely closing and fastening open-ended envelops and like receptacles.

The present invention consists in a cap-shaped closure of novel construction, as hereinafter set forth and claimed.

15 The leading object of the invention is to provide merchants and others with a closure attachment for such envelops and the like, hereinafter mentioned simply as "envelops," adapted to be made of any desired distinctive 20 color or with any desired distinctive ornamentation and to be readily attached to the envelops by unskilled hands, so that the envelops and closure attachments may be kept in stock separately and furnished as required.

25 Another object is to facilitate constructing such closure attachments of tough paper or similar flexible material in one piece by reinforcing the material where strength is especially required, and thus to obviate using relatively heavy and expensive material.

30 Other objects are to fasten down the reinforcing-folds by a pair of eyelets serving also as parts of the fastening means and to provide the closure with a tension fastener conveniently and effectively arranged.

35 A sheet of drawings accompanies this specification as part thereof.

Figure 1 is a perspective view of a cap-shaped closure attachment, illustrating the 40 invention. Fig. 2 is a face view of the blank from which such closure attachment is made in one piece and in the preferred manner hereinafter set forth. Fig. 3 is a view of the inner side of the closure attachment made 45 from such blank as it appears unfolded or open and unattached. Fig. 4 is a view of the other side of the same closure attachment, showing the same attached to an envelop. Figs. 5, 6, and 7 are elevations of closure attachments, illustrating modifications of the 50 invention.

Like letters and numbers refer to like parts in all the figures.

In carrying this invention into effect

blanks are made of the form represented by Fig. 2, the same being cut flat from suitable tough paper or from cloth, silk, satin, or other suitable flexible material to correspond with that of which the envelop is made, and the closure attachment is completed by folding the blank along three lines, (represented, respectively, by dotted lines at 1, 2, and 3 in Fig. 2,) so as to provide the attachment with a reinforced straight edge *a* and a pair of reinforced oblique edges *b* and *c*, which become outer edges when the attachment is in place on a receptacle. The material is also provided with creases 4, 5, and 6 along lines represented by dotted lines correspondingly numbered in Fig. 2, so as to outline its front 70 or body portion *d*, which is of oblong rectangular shape.

The other portions of the closure formed by said blank are an attaching portion *e*, adjoining said body portion *d* along the edge formed by said crease 4, the same being one of its longer edges, and a pair of laterally-folding flaps *f* and *g*, adjoining the ends of said body portion *d* at said creases 5 and 6.

A pair of eyelets *h* and *i* serve to fasten 80 down the folds which form reinforced edges *a*, *b*, and *c*, as shown in Fig. 3, and also serve conveniently and preferably to attach the disks *j* and *k* of a tension fastener, the string *l* of which is attached to one of the 85 eyelets in customary manner.

The attaching portion *e* is secured to the front or back of the envelop (represented at *B* in Fig. 4) by gum carried by said attaching portion, as indicated in Fig. 3, or by a central 90 eyelet or like fastening, the only requisites being that the closure attachment *A* shall be inseparably secured to the envelop *B* and that the crease 4 between the attaching portion *e* and body portion *d* shall be located at 95 or above and parallel with the square open end *x* of the envelop.

To close the envelop, the body portion *d* of the closure attachment *A* is folded over the open end of the envelop *B*, and the flaps *f* and *g* are folded toward each other so as to restore the closure attachment to the shape represented in Fig. 1, which is the shape in which it is handled as an article of manufacture and in which it is adapted to and in use serves to inclose the open end *x* of the envelop, to locate the fastening device *h-l* at a sufficient distance from the open end *x* for

ample security, and to reinforce the line of strain of the fastening device, so as to keep the closure attachment from tearing.

In the species represented by Figs. 1 to 4, 5 inclusive, a tension fastening device *h*' is employed, as aforesaid, and the laterally-folding flaps *f* and *g* are so proportioned that when the envelop is closed and fastened the ends of the flaps come together at the middle 10 of the envelop and closure, as shown in Fig. 1.

The laterally-folding flaps *f* and *g* may be thus proportioned for other forms of fasteners, as illustrated by Figs. 5 and 6, in which, respectively, a metallic fastener is represented 15 at *m* and a fastening-string at *n*, in connection with a pair of eyelets *h* and *i*, as before described.

In the species represented by Fig. 7 the laterally-folding flaps *f* and *g* are elongated, so 20 as to overlap each other and to bring the pair of eyelets *h* and *i* into line with each other, so that a central T-shaped metallic fastener *o* or the like may extend through both flaps, as shown in the figure.

25 Having thus described said improvement, I claim as my invention and desire to patent under this specification—

1. A cap-shaped closure attachment, for an open-ended envelop or like receptacle, 30 made in one piece from tough paper or similar flexible material and comprising an oblong rectangular body portion, an attaching portion adjoining one of the longer edges of said body portion and adapted to be attached to the receptacle at the open end of the latter, a pair of laterally-folding flaps adjoining the ends of said body portion and having oblique outer edges, a reinforced straight edge common to said body portion 35 and said flaps, and means for connecting said flaps with each other, substantially in line with said reinforced straight edge, to fasten the closure.

2. A cap-shaped closure attachment, for 45 an open-ended envelop or like receptacle, made in one piece from tough paper or similar flexible material and comprising an oblong rectangular body portion, an attaching portion adjoining one of the longer edges of 50 said body portion and adapted to be attached to the receptacle at the open end of the latter, a pair of laterally-folding flaps adjoining the ends of said body portion and having oblique outer edges, a straight edge 55 common to said body portion and said flaps reinforced by doubling the material upon itself, and means for connecting said flaps with each other substantially in line with said reinforced straight edge to fasten the 60 closure.

3. A cap-shaped closure attachment, for 65 an open-ended envelop or like receptacle, made in one piece from tough paper or similar flexible material and comprising an oblong 70 rectangular body portion, an attaching

portion adjoining one of the longer edges of said body portion and adapted to be attached to the receptacle at the open end of the latter, a pair of laterally-folding flaps adjoining the ends of said body portion and having oblique outer edges reinforced by doubling the material upon itself, a similarly-reinforced straight edge common to said body portion and said flaps, and means for connecting said flaps with each other comprising 75 eyelets which serve also to fasten down the folds of said reinforced edges.

4. A cap-shaped closure attachment, for an open-ended envelop or like receptacle, 80 made in one piece from tough paper or similar flexible material and comprising an oblong rectangular body portion, an attaching portion adjoining one of the longer edges of said body portion and adapted to be attached to the receptacle at the open end of 85 the latter, a pair of laterally-folding flaps adjoining the ends of said body portion and having oblique outer edges, a reinforced straight edge common to said body portion and said flaps, and a tension fastener arranged to connect said flaps with each other 90 substantially in line with said straight edge.

5. A cap-shaped closure attachment, for an open-ended envelop or like receptacle, 95 made in one piece from tough paper or similar flexible material and comprising an oblong rectangular body portion, an attaching portion adjoining one of the longer edges of said body portion and adapted to be attached to the receptacle at the open end of 100 the latter, a pair of laterally-folding flaps adjoining the ends of said body portion and having oblique outer edges reinforced by doubling the material upon itself, a similarly-reinforced straight edge common to said body 105 portion and said flaps, and a tension fastener arranged to connect said flaps with each other and comprising eyelets which serve to fasten down the folds of said reinforced edges, substantially 110 as hereinbefore specified.

6. A cap-shaped closure attachment, for an open-ended envelop or like receptacle, 115 made in one piece from tough paper or similar flexible material and comprising an oblong rectangular body portion, an attaching portion adjoining one of the longer edges of said body portion and adapted to be attached to the receptacle at the open end of the latter, a pair of laterally-folding flaps adjoining the ends of said body portion, a reinforced straight edge common to said body portion and said flaps and a tension fastener arranged to connect said flaps with each other substantially in line with said straight edge, substantially 120 as hereinbefore specified.

7. The combination with an open-ended 125 envelop or like receptacle, of a cap-shaped closure attachment made in one piece from tough paper or similar flexible material and comprising an oblong rectangular body por-

tion, an attaching portion adjoining one of the longer edges of said body portion and attached to the receptacle at the open end of the latter, a pair of laterally-folding flaps adjoining the ends of said body portion, a straight edge common to said body portion and said flaps, reinforced by doubling the material upon itself, and a tension fastening

5 arranged to connect said flaps with each other and comprising eyelets which serve to fasten down the fold of said reinforced edge, substantially as hereinbefore specified.
